CARBURETER.

1,149,035.

Specification of Letters Patent.

Patented Aug. 3, 1915.

Application filed January 7, 1913. Serial No. 740,612.

To all whom it may concern:

Be it known that I, EMILE EUGÉNE ERNEST Doué, a citizen of the Republic of France, and a resident of Villa des Lierres, 5 Collonges-sur-Saône, Rhône, France, have invented certain new and useful Improvements in Carbureters, of which the following is a specification.

This invention relates to carbureters for 10 internal combustion engines, founded upon the principle of progressive emulsion of the fuel by the means of additional air progressively admitted in the feed pipe of the fuel in a quantity increasing as the speed 15 of the motor increases. This automatic emulsion of the fuel does not give a rigorously constant charge of the mixture at every stroke, but that which is better, gives a more favorable ratio between the weight 20 of the sucked-in air and that of the vaporized fuel.

Figures 1 and 2 show diagrammatic vertical sections of two forms of apparatus for carrying out the new process.

Referring first to Fig. 1, the apparatus 25 comprises a pipe which receives the fuel by a calibrated nozzle 2 in the bottom of the fuel tank 3, and then rises to almost the height of the constant level in the form of a 30 siphon or inverted U, and passes thence down beneath the tank to the spraying nozzle 4. The two branches of the siphon go through the bottom of an air chimney 5 which surrounds them, and of which the 35 upper end is open to the air in the upper part of the tank which is open to the atmosphere through the air hole 3^a. The ascending branch 6 is perforated with holes 7 well calibrated and placed at regular distances 40 along its length. Another nozzle 8 feeds besides the pipe 1 between the siphon and the spraying nozzle 4. When the engine is at rest, the fuel enters the pipe 1 by means of the nozzle 2 and by the ports 7 and fills 45 the air chimney 5 to the height of the constant level, closing the ports 7 against the entrance of air. As soon as the engine is started, the suction is exercised on the spraying nozzle 4, which is fed by the nozzle 8 50 and also by the siphon completely immersed in the fuel; the mixture is therefore very rich as is desirable for slow running, with heavy loads, heavy grades and for starting. As soon as the engine increases its speed, the 55 liquid in the air chimney 5 being drawn out, opens one or more, according to the speed,

of the air ports 7, thereby permitting increasing emulsion of the fuel. As soon as the speed of the engine decreases, the ports 7 for the admission of air are again progressively closed by the liquid, thereby more and more enriching the mixture as the engine slows down. The nozzle 2 of the siphon might also be placed in the base of the air chimney 5; however the suction of the 60 fuel by the siphon would be in that case less direct at very high speeds, than with the nozzle placed on the bottom of the tank at the end of the siphon.

Another simple and practically built arrangement consists in the substitution of the proper siphon by two concentric pipes (Fig. 2) for which the best place is in the center of the tank. A vertical suction pipe 9 open at its upper end and screwed on the channel 10, is surmounted by another closed pipe 11 forming a bell and provided with holes along its length for the admission of air. The two concentric pipes 9 and 11 are surrounded, quite close to their base by the air 70 chimney 13 open to the air admitted through air holes 3^a and 3^b, the nozzle 14 of the siphon being placed in the base of the pipe 11 in order to communicate directly with the tank below the air chimney 13. 75

The shapes, sizes and relative ratios of the parts of the described system may be modified in accordance with the various industrial application to which it may be adapted without departing from the invention as claimed. 80

I claim:

1. In a carbureter, the combination of a tank; a chimney therein open at the top; and a pipe having a delivery nozzle at one 95 end, and an inlet nozzle communicating with the tank, a part of said pipe between said nozzles being bent upwardly and forming a siphon in said chimney and provided with openings in the ascending arm. 100

2. In a carbureter, the combination of a tank; an air chimney open at the top; and a pipe having a delivery nozzle and an inlet nozzle communicating with the tank, said pipe being provided with a part extending upwardly within said air chimney and provided with openings communicating therewith, said pipe being provided with an additional inlet nozzle communicating with the tank between said part and the delivery 110 nozzle. 105

3. In a carbureter for internal combustion

motors, the combination of a tank; an air chimney therein, open at the top and having an orifice communicating with the tank; and a pipe provided with a siphon part arranged in said chimney below the normal level of the fuel therein and provided with holes spaced along its length, the fuel serving to obturate said holes during slow running or stoppage of the motor and to admit air into the pipe when the speed of the motor increases and the said orifice feeding the siphon does not supply sufficient fuel to maintain the fuel in the chimney at the height of said normal level, the number of holes uncovered varying in accordance with the speed of the motor.

4. In a carbureter for internal combustion engines, the combination of a tank; an air chimney therein, open at the top and communicating with the tank; and a pipe provided with two orifices communicating directly with the tank, said pipe being formed into a siphon part within the chimney and between said orifices, the siphon part having holes spaced along its leg, most distant from the outlet of the conduit, said orifice nearest the outlet serving to supply pure fuel only at all times from said tank of which the quantity diminishes proportionally as the speed increases, the orifice most distant from the outlet of the conduit supplying pure fuel at slow speed, this fuel being emulsified with air at high speed by air entering said holes

as fuel is withdrawn from the chimney faster than it enters, whereby the proportion of air to fuel increases as the speed increases and the air passing through the conduit retards the flow of fuel through the orifice nearest the outlet.

5. A carbureter for internal combustion engines characterized by the nozzle being fed by a single conduit provided with two fuel supply orifices both in direct communication with the fuel container, one of said orifices always supplying fuel of which the quantity diminishes proportionally as the speed of the motor increases, while pure fuel is supplied at the same time by way of the conduit from the other orifice at slow speed of the motor, this fuel being emulsified by air on its passage through the conduit when the speed of the motor increases, by means of a siphon shaped part disposed in a chimney open to the air and provided with holes spaced along its length, the proportion of the air relative to the fuel supply increasing with the speed of the motor, the air thus introduced into the conduit having the effect of reducing proportionally the fuel supply by the first orifice.

In testimony whereof I affix my signature in presence of two witnesses.
